PATENTED FEB. 4, 1908.

No. 878,328

C. T. ARNOLD.
CAR AXLE JOURNAL BOX.
APPLICATION FILED MAY 6, 1907.

UNITED STATES PATENT OFFICE.

CLAYTON T. ARNOLD, OF WILKES-BARRE, PENNSYLVANIA.

CAR-AXLE JOURNAL-BOX.

No. 878,328.

Specification of Letters Patent.

Patented Feb. 4, 1908.

Application filed May 6, 1907. Serial No. 372,188.

To all whom it may concern:

Be it known that I, CLAYTON T. ARNOLD, a citizen of the United States, residing at Wilkes-Barre, in the county of Luzerne and State of Pennsylvania, have invented certain Improvements in Car-Axle Journal-Boxes, of which the following is a specification.

My invention is an improvement in journal boxes of that class which are especially adapted for use on railway and street cars, and the primary object of my invention is to provide simple and effective means for protecting the bearing surfaces against the ingress of dirt or other foreign substances.

Other though minor objects of the invention will hereinafter appear, and what I claim as new in the particular construction and combination of parts is specifically set forth in the appended claims.

In the accompanying drawings, which form a part of this specification:—Figure 1 is a longitudinal sectional view through a car-axle journal-box, constructed in accordance with my invention. Fig. 2 is a transverse sectional view on the line 2—2 of Fig. 1. Like numerals of reference indicate like parts in all the figures of the drawings.

As shown in the drawing my invention is applied to a journal box having an upper oil chamber or reservoir 2, a lower chamber 3 which receives the end of the car-axle, and a compartment 4 at the rear end of the box, said compartment being adapted to contain the guard-plates and holders therefor, hereinafter particularly described. The chambers 2 and 3 are each provided near the upper end of the front wall thereof with an opening, said openings being designated as 5 and 6, respectively, and are closed by a hinged door 7, having the usual rubber blocks 7^a.

The upper wall or top of the journal-box is shaped to receive the arch-bars 10 and 11, between which and the lower bar 12 the box is clamped by the bolts 13, as is usual. The bottom of the box is provided with an outlet opening 8, through which the oil which drips from the axle and collects in the bottom of the chamber 3 may be drawn off, said opening being closed by means of a removable screw plug 9.

The chambers 2 and 3 are separated by a partition 14, against the under side of which bears a block 16 forming the bearing for the axle 18, said partition and block having an

oil feeding aperture 21 leading to the usual oil-groove 23 in the block.

The axle extends into the journal-box through the openings 25 at opposite sides of the vertical compartment 4, and in order to prevent dirt and other foreign matter from entering the box through these openings I provide the removable guard-plates 26 and 27, one of which, as 26, bears against the upper side of the axle, while the other, as 27, bears against the underside thereof, and these guard-plates are provided with flanges 28 which overlap, as indicated in dotted lines Fig. 1, so as to give a tight joint and allow for wear. These guard-plates are held in close yielding contact with the axle by means of springs, the lower plate 27 being pressed against the axle by means of the springs 30 which bear against opposite ends of said plate, a protecting metal strip 31 being interposed between the springs and guard-plate so as to protect the latter when it is made of papier-mâché or other material that would be worn by the ends of the springs. The guard-plate 26 is held in place by a single spring 32, which is interposed between a protecting metal strip 33 on said guard-plate and a removable securing device 34, the latter being of such construction that it may be easily placed in engagement with and detached from the journal box. This device therefore comprises a horizontal strip 34^a, with which the spring 32 engages, and at the ends of said strip are downwardly and outwardly inclined members 35 which bear at the bottom of recesses therefor in the ends of the guard-plate and are integrally connected to upwardly projecting spring members or catches 36, each having a shoulder 37 engaging a stop shoulder 38 at the upper end of the vertical compartment 4. Beyond the shoulder 37 the spring member or catch is curved outwardly, as shown, to form a grasping portion. Each spring member or catch 36 is also provided with a projecting arm 39 which bears upon the horizontal portion 34^a and has a tendency to force the spring member or catch outward and into engagement with the flange so as to securely lock the device. The part 34^a of the securing device and the protecting metal plate 33 are each provided with a boss 40, and said bosses enter the ends of the compression spring 32 so as to retain the same in position.

It will be readily seen that when it is desired to remove the upper guard-plate, either for the purpose of renewing said plate or removing the journal-box from the axle, it is only necessary to first remove the securing device, and this is accomplished by simply grasping the spring members or catches 36 and pressing them towards each other until they disengage the stop-shoulders 38, when the said device is free to be withdrawn. After the securing device is withdrawn the guard-plate may be removed vertically from the compartment. When the guard plates are in place they cover the openings 25, and being held in close contact with the axle will effectually prevent the ingress of any dirt, grit or other substance, thus protecting the bearing surfaces from foreign matter.

From the foregoing description, in connection with the accompanying drawings, the construction, operation and practical advantages of my invention will be readily understood, and it will be noted that the lubrication and protection of the bearing surfaces of the axle and bearing-block is very effective; and that the parts which are subject to wear, to wit, the guard-plates 26 and 27 are readily removable so that they may be renewed.

Having thus described my invention, what I claim as new and desire to secure by Letters-Patent, is:—

1. In a car-axle journal box, the combination with a box having a vertical compartment open at its upper end and through which compartment the axle is adapted to pass transversely, and provided with stop-shoulders at the upper ends of the compartment, of guard-plates slidably and removably mounted in the compartment and having overlapping flanges, springs interposed between the lower guard plate and bottom of the compartment, a removable securing device located in the upper end of the compartment and having spring members engaging the stop-shoulders, and a spring interposed between the securing device and upper guard-plate.

2. In a car-axle journal box, the combination with a box having a vertical compartment open at its upper end and through which compartment the axle is adapted to pass transversely, and provided with stop-shoulders at the upper ends of the compartment, of guard-plates slidably and removably mounted in the compartment and having overlapping flanges, springs interposed between the lower guard-plate and bottom of the compartment, a removable securing device located in the upper end of the compartment and having spring members engaging the stop-shoulders, and a boss formed on its inner side, a wear-plate bearing upon the guard-plate and having a boss on a line 65 with the aforesaid boss, and a helical spring

interposed between the securing device and guard-plate and engaging the bosses, substantially as shown and described.

3. In a car-axle journal box, the combination with a box having a vertical compartment open at its upper end and through which the axle passes transversely, and provided with stop-shoulders at the upper end of the compartment, of guard-plates slidably in the compartment and having overlapping flanges, springs interposed between the lower guard plate and the bottom of the compartment, a removable securing device located in the upper end of the compartment and comprising a horizontal portion having downwardly and upwardly projecting spring members, the upwardly projecting members having shoulders which engage the stop-shoulders of the box and terminate in hand-grasping portions, and a spring interposed between the horizontal portion of the securing device and the upper guard-plate, substantially as shown and described.

4. In a car-axle journal box, the combination with the axle and box, the latter having a vertical compartment open at its upper end and through which compartment the axle passes transversely, and provided with stop-shoulders at the upper end of the compartment, of guard-plates slidably in the compartment to embrace the axle and having overlapping flanges, springs interposed between the lower guard-plate and bottom of the compartment, a removable securing device located in the upper end of the compartment and comprising a horizontal portion having downwardly and upwardly projecting spring members at its ends, the upwardly-projecting members having shoulders which engage the stop-shoulders of the box 105 and the horizontal portion of the securing device having a boss on its underside, a wear-plate bearing on the upper guard-plate and having a boss on its upper side, and a helical spring interposed between the 110 securing device and wear-plate and engaging at its ends with the aforesaid bosses.

5. In a car-axle journal box, the combination, with a box having a vertical compartment at its rear end through which the axle 115 passes transversely, the opposite end walls of said compartment having stop shoulders at their upper ends, of guard-plates slidably mounted in the vertical compartment and adapted to bear against the upper and lower 120 sides of the axle and having overlapping flanges, springs interposed between the bottom of the compartment and lower guard plate, and a securing device for the upper guard plate comprising a horizontal portion 125 with downwardly projecting members at its outer ends integrally connected to upwardly-projecting spring members or catches having shoulders which engage the stop shoulders at the upper ends of the compartment, and 130

arms projecting from said spring members or catches and bearing upon the horizontal portion of the securing device, together with a compression spring interposed between the said horizontal portion and the upper guard-plate, substantially as shown and described.

In testimony whereof I have signed my

name to this specification in the presence of two subscribing witnesses.
